Werner Block

UNITED STATES PATENT OFFICE.

ARTHUR SCHLOSSER, OF NEW YORK, N. Y.

ADVERTISING-SIGN.

1,396,467.

Specification of Letters Patent. Patented Nov. 8, 1921.

Application filed March 7, 1921. Serial No. 450,179.

To all whom it may concern:

Be it known that I, ARTHUR SCHLOSSER, a resident of New York city, Bronx county, State of New York, and a citizen of the 5 United States of America, have invented certain new and useful Improvements in Advertising-Signs, of which the following is a specification.

This invention relates to improvements 10 in advertising signs, one of the objects being to provide a sign arranged so that any desired advertising matter can be placed thereupon, preferably in the form of words made up of independent letters which are detachably connected to the supports therefor. A 15 further object of the invention is to provide means whereby letters of various sizes can be used. In other words, I arrange a supporting medium for letters constructed so 20 that it can be adjusted to receive carriers for letters of various sizes, whereby large or small letters can be used.

I will now proceed to describe my invention in detail, the novel features of which 25 I will finally point out in the appended claims, reference being had to the accompanying drawing, wherein:—

Figure 1 is a front elevation of my improvement, the frame and carriers being 30 broken away;

Fig. 2 is an enlarged vertical view, the frame being broken away, the section being taken on a line 2—2 in Fig. 1;

Fig. 3 is a vertical sectional view of the 35 frame member of the sign, the section being taken on a line 3—3 in Fig. 1, the supporting bars for the letter carriers being omitted;

Fig. 4 is a fragmentary perspective view 40 of one of the letter carrier supports;

Fig. 5 is a rear view of one of the letter carriers; and

Fig. 6 is a fragmentary sectional view 45 illustrating the means to retain the supporting bars, for the letter carriers, in position.

As herein embodied, my improved sign consists of a frame 7, supporting bars 8 and 9 which are adjustable longitudinally of the frame. I have herein illustrated but two, 50 bars, but as many can be employed as may be desirable. The bars 8 and 9 support carriers 10, each support being provided with a letter. The letters can be painted upon the carriers, or embossed or applied in 55 any manner desirable.

The side members 11 and 12 of the frame

8 are each provided with a groove 13 extending longitudinally thereof, as are also the end members 14 and 15, the grooves in members 14 and 15 being indicated by 16. 60 The wall at one side of the grooves 13 and 16 is provided with threaded openings 17 to receive a screw 18 (see Fig. 6) by means of which the bars 8 and 9 are held in position. The bars 8 and 9, at each end, slidably engage the adjacent groove 13; hence 65 they can be shifted along said grooves to vary the distance between said bars in order to accommodate carriers 10 of different lengths. Each opening 17 may carry a 70 screw 18, or one screw for each side 11 and 12 may be used; in this event the screw would be removed from one opening and applied to another in the event of the bars being adjusted. Each carrier 10 consists of 75 a plate, the ends of which engage a rabbet 19 formed along the adjacent edge of the bars 8 and 9, so that the surfaces of the bars and plate will be flush and also provide a backing member 20 to aid in supporting the carriers 10, said backing member 20 being the rear wall of the rabbet 19. 80

Each plate 10 carries a clip 21 of resilient metal, such as thin spring steel, brass, or other suitable material having yieldable 85 ends 22, preferably rounded. When the plates 10 are forced into the rabbets 19, the clips or rounded ends 22 will engage the backing 20 or rear wall of the rabbet 19 and hold the carriers in place. To remove 90 the carriers, it is but necessary to force them out of the rabbets 19.

Each longitudinal edge of each bar 8 and 9 is preferably provided with a rabbet 19 to coöperate with a similar bar should more 95 than two bars be used in a sign. The carriers 10 will be made in different sizes, and, of course, blank carriers will be used as spacing elements between the words of an advertisement. 100

Having described my invention, what I claim and desire to secure by Letters Patent is:—

1. In a sign, frame members provided with grooves, extending longitudinally thereof, bars extending across said frame having the ends thereof in slidable engagement with a groove in an adjacent frame member, means to secure the bars in adjusted positions in said grooves, each of said 105 bars being provided with a rabbet extending longitudinally thereof, carriers for ad- 110

vertising matter arranged to engage said rabbits, and resilient clips carried by the carriers to releasably engage the rear wall of said rabbits.

5 2. In a sign, frame members provided with grooves, extending longitudinally thereof, bars extending across said frame having the ends thereof in slidably engagement with a groove in an adjacent frame

member, set screws to secure the bars in 10 adjusted positions in said grooves, carriers for advertising matter arranged to be applied to said bars, and clips carried by the carriers to releasably engage the bars.

In testimony whereof I hereunto affix my 15 signature.

ARTHUR SCHLOSSER.
